UNITED STATES PATENT OFFICE.

WILLIAM J. NEIDIG, OF MADISON, WISCONSIN, ASSIGNOR TO NEIDIG TYPEWRITER CO.,
OF CHICAGO, ILLINOIS, A CORPORATION OF ILLINOIS.

TYPE-WRITING MACHINE.

1,053,929.

Specification of Letters Patent. Patented Feb. 18, 1913.

Application filed May 27, 1912. Serial No. 699,958.

To all whom it may concern:

Be it known that I, WILLIAM J. NEIDIG, a citizen of the United States, residing at Madison, in the county of Dane, State of Wisconsin, have invented a certain new and useful Improvement in Type-Writing Machines, of which the following is a specification, reference being had therein to the accompanying drawings.

10 Certain principles and features of my invention as described herein are included within the invention which is described and generically claimed in my co-pending application filed April 20, 1908, Serial No. 428,212.

15 One of the objects of my general invention is to indicate to the operator of a type-writing machine the decreasing distance from the current printing point to the bottom end of the sheet, or to another point on the sheet, during the progress of the sheet, and this without preliminary care on his part, automatically. This function I believe has never before been performed, but

20 is novel to my generic invention.

Additional objects are to supply the operator with other indicating means, comprising improved visual, audible and machine-lock signals given at predetermined

25 sheet-positions.

The present embodiment of the invention has as features certain novel combinations of sheet-controlled elements adapted to render the invention more useful under the various conditions of practice, as will be explained.

30 In the drawings,—Figure 1 is a side elevation of portions of a type-writing machine carriage, partly broken away, showing my invention as applied thereto, certain portions of the main frame also being indicated. Fig. 2 is a plan view of some of the parts shown in Fig. 1. Fig. 3 is a cross-section on the line 3—3 of parts shown in Fig. 4. Fig. 4 is a view chiefly in section on the line 4—4 of Fig. 3, looking in the direction of the arrows, and showing the drive mechanism actuating drum 6. Fig. 5 is a side elevation of a portion of a type-writer carriage showing a modification. Fig. 6 is a plan view of the same. Fig. 7 is a side elevation representing another modification. Fig. 8 is a front view of the same, the carriage being shown in section.

35 Referring to the drawings, the main

frame of the machine is indicated at 41, and the usual carriage frame, movable laterally as in practice upon the main frame, at 12. In the carriage frame at either end is journaled platen arbor 13, which bears fixedly 40 attached thereto in usual manner the type-writer platen 10, which as herein regarded is the principal feed-roll for feeding the sheet through the machine. The platen is connected as in practice with usual line-spacing mechanism, not shown herein, of any approved type. The paper-table for the support of the entering sheet is shown at 8, the same being carried in usual manner upon carriage-frame 12. This structure is 45 well-known to those skilled in the art and need not be more fully described. Against the platen head 39 at the end of platen 10 is affixed inner shell 11 so as to rotate in unison with said platen head and therefore 50 with the platen to which the platen head is attached. Independently journaled upon platen arbor 13 is drum 6, the laterally extending peripheral portion of which overlaps inner shell 11 and moves loosely thereon. Drum 6 consists of a peripheral or index-bearing portion, an upstanding portion, and a bushing portion, the upstanding portion being fixedly attached to the bushing portion 67. Upon the inwardly projecting 55 pins 53 on said drum are journaled the bell-levers 18 connected by means of the pins 16 with the friction-pieces 5. Springs 7 attached at one end to pins 4 on said drum engage at the other end with said bell-levers 60 pulling so as to tend to press friction-pieces 5 more or less firmly into radial engagement with inner shell 11, according as the end of the spring is inserted in one or another of the holes 17 in said bell-levers. 65 Drum 6 is conveniently maintained in lateral position by washer 19. A fixed projection 14 is mounted on said drum. 70 Carriage frame 12 bears the inwardly projecting pin or axle 20 on which is journaled sleeve 21. Fixedly attached to said sleeve near one end is stop 15 and fixedly attached near the other is paper-feeler 28, the parts being so mounted that a short slot or opening 4 in paper-table 8 lies underneath the 75 paper-feeler, and the end of stop 15 lies in the plane of projection 14. The spring 151 tends to move stop 15 out of the path of said projection and paper-feeler 28 into said slot, one end of said spring being attached 80

to carriage frame 12 and the other end engaging upon said stop. Carriage frame 12 bears also the inwardly extending pin 22, on which is journaled hub 23 bearing hammer-stem 24. Lever 25 having a weighted portion 31 is also journaled on pin 22, but outside of the plane of projection 14 on the drum. Lever 25 bears the pin 29, which engages upon said hammer-stem. An outwardly extending pin 30 is carried by drum 6 in such radial position as to engage with lever 25 but not to engage with stop 15. Pin 30 may be screwed into any one of the threaded holes 30', so as to engage with said lever earlier or later. Stem 24 bears bell-hammer 26 affixed to the free end thereof, and is given a U-form, downward, outward and upward, for convenience in bringing it adjacent to the bell 27, supported from carriage frame 12 on central pin 32. Carriage frame 12 bears also the inwardly extending pin 40, on which is journaled hub 72 having a downwardly extending portion 43, a jointed lever-portion 1, and a lever-portion 45. Said downwardly extending portion 43 and pin 40 may be regarded as representing similar parts on the carriage frame at the opposite end of the platen, as will be understood, the said parts 43 being joined by the laterally extending part 42 so as to form a rocking bail-piece. The portion 42 of this bail-piece is supplied with teeth 44 alternating with interdental spaces. Attached to the carriage track 50 about midway laterally between the stationary frames 41 of the machine is the stop 48 having a toothed portion 49, the arrangement being such that when bail 42 is rocked rearwardly on axis 40, teeth 44 will pass on either side of tooth 49. Lever 45 is continued rearwardly, and rests by gravity against stop 47 on carriage frame 12. Lever 1 is mounted in such a plane as will not engage it with projections 14 and 30 aforesaid. Coöperating with said lever is projection 68 which may be screwed into one or another of the threaded holes 68' in the upstanding portion of drum 6 so as to be angularly adjustable on said drum. It will be understood that pin 68 has a radial position permitting it to clear lever 25 and stop 15.

The action of the mechanism is as follows: The sheet of paper 33 is placed upon the paper-table 8 in usual manner and advanced toward the platen for entering into the machine. This action carries the leading edge of the sheet under paper-feeler 28 so as to raise said paper-feeler out of slot 4, the paper-feeler being light and suitably shaped and moreover projecting into the slot only a short distance. This action rocks sleeve 21 and moves stop 15 upwardly until it lies in the path of projection 14, against the action of the light spring 15¹. All these parts are constructed as light as possible so as to

reduce inertia, and the spring-action is extremely light. It is found in practice that by such use of the leading edge of the sheet the operator is able to move the lightly poised stop 15 into the path of projection 14 without the exercise of additional care. The sheet will be advanced through the machine by the platen as usual. The turning of the platen causes drum 6 to rotate, friction-member 11 being in engagement with the coöperating friction-member 5 and acting drivingly thereon. This rotation of drum 6 will eventually bring projection 14 against stop 15 in its path. Drum 6 will thereafter be maintained in a stationary position during the presence of stop 15 in engagement with projection 14, and in this position it will remain until the bottom end of the sheet passes from under paper-feeler 28. Upon the passing of the sheet-end, paper-feeler 28, no longer controlled by the sheet, and under the actuation of spring 15¹, will enter slot 4, and stop 15 will be withdrawn from the path of projection 14. Drum 6 under its frictional actuation will now be given movement simultaneous with that of the platen.

Since the end of the paper-feeler 28 must intersect the paper path so that the paper-feeler is always released when the end of the sheet is a fixed distance from the printing point, drum 6 must begin its movement when the bottom edge of the sheet is a fixed distance from the printing point, and as the drum maintains always a line by line progress thereafter with the sheet, since it moves with the platen and the platen advances the sheet, it must bring always the same point on its periphery opposite pointer 34, attached to carriage frame 12, when the end of the sheet attains any given distance from the printing point. This distance, whatever it be, can be determined, and can be indicated by an index on the drum or index-carrier 6, so that the distance from the end of the sheet to the printing point will be indicated step by step from the time paper-feeler 28 is released by the sheet until the sheet leaves the machine, or as long as desired. The kind of indices employed, and the unit of measurement, will be as may be preferred. I prefer to use numerals for indices, arranged in descending order as shown in the drawing. It is of course immaterial whether the movable indices come to rest exactly opposite the stationary index or pointer, or whether the indices in themselves signify distance units, or indicate the entire remaining distance to the bottom edge of the sheet or only part of it.

I usually employ for a stationary index a shield-pointer, that conceals one portion of the carrier from the operator, and the carrier itself is divided into two different ap-

pearing segments, one of which is visible to the operator during the detained position of the carrier, and the other of which is not visible but lies behind the shield-pointer in that position of the carrier. In my drawings I show the first named of these segments as containing no indices except the circular index 89, and by preference, I color this segment black, and the second of these segments, which I cause to bear indices, I prefer to supply with a ground of white. When the sheet end releases the carrier or drum, and the white index-bearing segment comes into view, the change from black to white attracts the operator's attention and he knows that the end of the sheet is within a given distance from his printing point. It is not essential that the white segment should come into view at the very first feed-movement after the release of the carrier.

My audible and machine-lock signals are given as follows: At the predetermined time after the release of drum 6 to move with the platen, projection 30 engages with lever 25, rocking the same upon pin 22 and through the engagement of projection 29 upon hammer-stem 24 moving the bell-hammer 26 away from bell 27 until pin 30 clears lever 25, whereupon hammer 26 falls by gravity against bell 27 and gives the operator an audible signal as to his sheet position. My machine-lock signal is given as follows: At the predetermined time, projection 68 engages with lever 1, thereby pressing lug 71 against hub 72 and rocking said hub and the attached bail-piece 42 upon pin 40 until teeth 44 are brought into engagement with tooth 49 on the machine frame. The carriage is thereby locked against lateral movement, the typewriter mechanism rendered inoperative, and the operator warned that it is time to remove his sheet. In case he should desire to print another line upon that sheet he has only to turn his platen forwardly until lever 1 is released by pin 68 and then backwardly into the desired line position. The parts on pin 40 will instantly return by gravity into the position shown in Fig. 1, releasing the machine for further use.

It will be noted that the mechanism described can be backed up from any position and to any required extent. Stop 15 is constructed with a beveled head and with a double bend or offset in the shaft portion thereof. In case of backward actuation of projection 14 against stop 15 during the presence of the sheet under the paper-feeler, stop 15 will lift and permit projection 14 to pass thereunder, and when the projection comes to the offset portion of the stop the stop will be released by the projection and return into detaining position. Backing-up of projection 30 past lever 25 is provided for through the give-way engagement of pin

29 upon hammer-stem 24, said parts separating in such a movement and the weighted portion 31 of said lever returning the parts into position after the passing of said projection. Backing-up of projection 68 past lever 1 is provided for, lever 1 bending backward on pin 71, lug 70 separating from hub 72 so as to permit of the action.

I usually station my paper-feeler over the paper table 8, and usually so mount the parts that stop 15 will move in a plane coinciding with the plane of projection 14, but the position and form of these parts may vary, as may the specific form of means employed to give the index-carrier or drum movement after its release by the stop. In the Figs. 5 and 6 I show a typical modification in the manner of mounting the feeler and stop parts referred to. The index-carrier 6^a and its frictional driving mechanism are essentially the same as described hereinbefore. The platen head 39^a is here made thicker in order to hold the carrier farther away from the end of the platen and give room for the action of the parts. Attached to carriage frame 12 is frame-extension 42 bearing pin 20^a journaled upon which is bell-lever 64. One arm of said bell-lever has attached thereto the paper-feeler 28^a having action into slot 4 in paper table 8. The other arm of said bell-lever is mortised. Pivoted in the mortise by means of pin 20^a is stop 15^a, lugs 62 and 63 limiting the movement of the stop upon said pin. A spring 15², one end of which engages upon said bell-lever and the other end of which is attached to frame-extension 42, tends to rock said bell-lever so that stop 15^a takes a position out of the path of projection 14^a and paper-feeler 28^a a position in slot 4. When the paper sheet is entered down paper table 8, the leading edge thereof raises paper-feeler 28^a out of slot 4, thereby moving stop 15^a into the path of projection 14^a. In this position the stop cooperates with the said projection to stop carrier 6^a. When the end of the sheet passes the paper-feeler, stop 15^a is withdrawn from projection 14^a by the action of spring 15² and the carrier thereupon begins its movement with the platen and thereafter performs its indicating functions, which are identical with those of carrier 6 of the earlier figures.

In Figs. 7 and 8 I show how the paper-feeler may be mounted underneath the platen. Attached upon carriage frame 12 is frame extension 43 supporting the two ends of pin 20^b. Journaled upon said pin is sleeve 21^a having fixedly attached thereto near one end the lever 64^a and fixedly attached thereto near the other end the lever 15^c. Lever 64^a has attached thereto at its free end the upwardly extending paper-feeler 28^a, having a path into the circumferential slot 4^a in the platen. Lever 15^c is

mortised to receive stop 15^b, said stop being journaled on pin 20^c and having a lug 62^a to limit its movement on said pin. Said stop is supplied with an ear 54 for one end of spring 15^a, the other end of the spring being attached to pin 55 on frame-extension 43, said spring tending to pull said parts together. Normally the parts assume the position shown in Fig. 7, with the paper-feeler projecting into slot 4^a and stop 15^b maintained out of the path of projection 14, spring 15^a giving the parts such position. The sheet is entered as usual into the machine. When the leading end thereof encounters paper-feeler 28^b it lifts said paper-feeler out of the paper path and moves stop 15^b into the path of projection 14, which eventually will be stopped or detained thereby as before. Upon the passing of the sheet-end the paper-feeler will enter the slot, stop 15^b will be retracted from projection 14 by the spring, and carrier 6 will begin its movement with the platen, as before, and perform its indicating functions. Backing-up in these modifications is provided for. In case of stop 15^a of Figs. 5 and 6, projection 14^a lifts the stop out of its path, the lug 62 separating from lever 64 and permitting the movement. In the case of stop 15^b in Figs. 7 and 8, essentially the same action occurs, lug 62^a separating from lever 15^c when the projection is backed against said stop and permitting give-way movement of the stop.

It is to be noted that provision is made in all the embodiments shown for the backing-up of the sheet after the feeler has been released thereby. In case of the paper-feelers shown in Figs. 1 to 6 the bottom edge of the sheet in a backing-up movement will be switched into an open by-path out over the top of the feeler. In the embodiments shown in Figs. 5 and 6 the backing-up bottom edge of the sheet will lift the paper-feeler out of its slot just as the leading edge will do when the sheet is entered. It is to be noted also that in practice an operative member like drum 6 that is given movement with the usual abruptly starting and stopping platen tends to creep or drift in line-space direction relatively to the platen, and that the friction-drive herein shown is especially adapted to check any such tendency, such movement on the part of the member acting toggle-wise to increase the friction between the member and its driver.

The devices shown in the drawing and described herein are part of a series of closely related inventions or improvements which are presented in a number of co-pending applications for Letters Patent filed by me. The said devices have a number of general objects in common with those forming the subject-matter of different applications in

the said series, and to a certain extent embody and utilize various principles and features which are common to the devices shown and described in one or another of the said applications. Some of the said common principles and features are claimed broadly in my application filed April 20, 1908, aforesaid, and in my applications filed Dec. 15, 1909, Serial No. 533,309; Dec. 22, 1909, Serial No. 534,559; April 25, 1910, Serial No. 557,330; March 30, 1912, Serial No. 687,463; April 4, 1912, Serial No. 688,358; and April 9, 1912, Serial No. 689,560. The branch of the general invention that is covered hereby is distinguished by the characteristic features specified in the following claims.

I claim as new and desire to secure by Letters Patent:—

1. In a typewriting machine, in combination, a platen, a detainable revoluble member, indicating means called into operation through said member, means for giving said member simultaneous movement with the platen, a paper-feeler movable out of the paper path by the leading edge of the sheet, and a stop maintained in the path of said revoluble member by said paper-feeler in the presence of the sheet. 85
2. In a typewriting machine, in combination, a platen, a detainable revoluble member having a projection in connection therewith, indicating means called into operation through said member, means for giving said revoluble member movement correlated with that of the platen, a paper-feeler movable out of the paper path by the leading edge of the sheet, and a stop maintained in the path of said projection by said paper-feeler in the presence of the sheet and spring-actuated out of the path thereof upon the passing of the sheet-end. 90
3. In a typewriting machine, in combination, a platen, an index-carrier bearing a detent, means for giving said carrier simultaneous movement with the platen, a paper-feeler movable out of the paper path by the leading edge of the sheet, and a movable stop maintained in the path of said detent by said paper-feeler in the presence of the sheet and releasing said detent upon the passing of the sheet end. 105
4. In a typewriting machine, in combination, a platen, an index-carrier having a projection in connection therewith, means for giving said carrier movement correlated with that of the platen, a paper-feeler movable out of the paper path by the leading edge of the sheet, and a stop maintained in the path of said projection by said paper-feeler in the presence of the sheet and spring-actuated out of the path thereof upon the passing of the sheet-end. 110
5. In a typewriting machine, in combination, a platen, a detainable member having a 120

125

- detent, visual signaling means called into operation through said member, means for giving said member simultaneous movement with the platen, a paper-feeler movable out of the paper path by the leading edge of the sheet, and a stop maintained in the path of said detent by said paper-feeler in the presence of the sheet and releasing said detent upon the passing of the sheet-end. 5
- 10 6. In a typewriting machine, in combination, a platen, a detainable revoluble member bearing a projection, visual signaling means called into operation through said member, means for giving said member simultaneous movement with the platen, a paper-feeler movable out of the paper path by the leading edge of the sheet, and a stop maintained in the path of said projection by said paper-feeler in the presence of the sheet and spring-actuated out of the path thereof upon the passing of the sheet-end. 70
- 15 7. In a typewriting machine, in combination, a platen, a detainable revoluble member having a projection in connection therewith, means for giving said member movement correlated with that of the platen, a paper-feeler movable out of the paper path by the leading edge of the sheet, a stop maintained in the path of said projection by said paper-feeler in the presence of the sheet and releasing said projection upon the passing of the sheet-end, and audible signaling means called into operation through said revoluble member. 80
- 20 8. In a typewriting machine, in combination, a platen, a detainable member having a projection thereon, a bell-striking means controlled by said member, means for giving said member simultaneous movement with the platen, a paper-feeler movable out of the paper path by the leading edge of the sheet, and a stop maintained in the path of said projection by said paper-feeler in the presence of the sheet and spring-actuated out of the path thereof upon the passing of the sheet-end. 85
- 25 9. In a typewriting machine, in combination, typewriter mechanism including a platen, a detainable revoluble member bearing a projection, means called into operation through said member for rendering the typewriter mechanism inoperative, means for giving said member simultaneous movement with the platen, a paper-feeler movable out of the paper path by the leading edge of the sheet, and a stop maintained in the path of said projection by said paper-feeler in the presence of the sheet and releasing said projection upon the passing of the sheet-end. 90
- 30 10. In a typewriting machine, in combination, typewriter mechanism including a platen, a detainable revoluble member bearing a projection, means called into operation through said member for rendering the typewriter mechanism inoperative, inoperative, means for giving said member simultaneous movement with the platen, a paper-feeler movable out of the paper path by the leading edge of the sheet, and a stop maintained in the path of said projection by said paper-feeler in the presence of the sheet and spring-actuated out of the path thereof upon the passing of the sheet-end. 95
- 35 11. In a typewriting machine, in combination, a platen, an index-carrier having a detent, means for giving said carrier movement correlated with that of the platen, a paper-feeler, and a stop maintained in the path of said detent by said paper-feeler in the presence of the sheet and spring-actuated out of the path thereof upon the passing of the sheet-end. 100
- 40 12. In a typewriting machine, in combination, a platen, a detainable member bearing a detent, visual signaling means called into operation through said member, means for giving said member simultaneous movement with the platen, a paper-feeler, and a stop maintained in the path of said detent by said paper-feeler in the presence of the sheet and spring-actuated out of the path thereof upon the passing of the sheet-end. 105
- 45 13. In a typewriting machine, in combination, a platen, a detainable member having a projection thereon, audible signaling means called into operation through said member, means for giving said member simultaneous movement with the platen, a paper-feeler, and a stop maintained in the path of said detent by said paper-feeler in the presence of the sheet and spring-actuated out of the path thereof upon the passing of the sheet-end. 110
- 50 14. In a typewriting machine, in combination, a platen, a detainable member supplied with a projection, indicating means called into operation through said member, means for giving said member simultaneous movement with the platen, a paper-feeler movable out of the paper path by the leading edge of the sheet, and a stop maintained in the path of said projection by said paper-feeler in the presence of the sheet and said parts constructed to permit backing-up from any position and to any required extent. 115
- 55 15. In a typewriting machine, in combination, a platen, a detainable member bearing a projection, indicating means called into operation through said member, means for giving said member simultaneous movement with the platen, a paper-feeler, and a stop maintained in the path of said projection by said paper-feeler in the presence of the sheet, and spring-actuated out of the path thereof upon the passing of the sheet-end, said parts constructed to permit backing-up from any position and to any required extent. 120
- 60 16. In a typewriting machine, in combination, typewriter mechanism including a platen, a detainable revoluble member bearing a projection, means called into operation through said member for rendering the typewriter mechanism inoperative, inoperative, means for giving said member simultaneous movement with the platen, a paper-feeler movable out of the paper path by the leading edge of the sheet, and a stop maintained in the path of said projection by said paper-feeler in the presence of the sheet and spring-actuated out of the path thereof upon the passing of the sheet-end, said parts constructed to permit backing-up from any position and to any required extent. 125
- 65 17. In a typewriting machine, in combination, typewriter mechanism including a platen, a detainable revoluble member bearing a projection, means called into operation through said member for rendering the typewriter mechanism inoperative, inoperative, means for giving said member simultaneous movement with the platen, a paper-feeler movable out of the paper path by the leading edge of the sheet, and a stop maintained in the path of said projection by said paper-feeler in the presence of the sheet and spring-actuated out of the path thereof upon the passing of the sheet-end, said parts constructed to permit backing-up from any position and to any required extent. 130

- 6
16. In a typewriting machine, in combination, a platen, a detainable member, indicating means called into operation through said member, frictional actuating means for said member, including friction members engaging through centrifugally-acting spring pressure, and a sheet-controlled stop for controlling the movement of the detainable member.
17. In a typewriting machine, in combination, a platen, a detainable member, indicating means called into operation through said member, frictional actuating means for said member, including friction members engaged by a toggle-joint device, and a sheet-controlled stop for controlling the movement of the detainable member.
18. In a typewriting machine, in combination, a platen, a detainable member, indicating means called into operation through said member, frictional actuating means for said member, including a device acting to increase the friction between said member

and its driver when the member is moved in one direction relatively to the driver so as to check the shifting of the member with respect to the driver, and a sheet-controlled stop for controlling the movement of the detainable member.

19. In a typewriting machine, in combination, a platen, a detainable member having a projection thereon, indicating means called into operation through said member, means for giving said member simultaneous movement with the platen, a paper-feeler, and a stop maintained in the path of the detainable member by said paper-feeler, said stop constructed with an offset therein adapted to provide passage for said projection in backing-up.

In testimony whereof I affix my signature in presence of two witnesses.

WILLIAM J. NEIDIG.
